UNITED STATES PATENT OFFICE.

SAMUEL J. LARGE, OF BRISTOL, CONNECTICUT, ASSIGNOR TO THE AMERICAN SILVER COMPANY, OF BRISTOL, CONNECTICUT, A CORPORATION OF CONNECTICUT.

DESIGN FOR A HANDLE FOR SPOONS, FORKS, OR SIMILAR ARTICLES.

45,066.

Specification for Design.

Patented Dec. 23, 1913.

Application filed October 13, 1913. Serial No. 795,017. Term of patent 3½ years.

To all whom it may concern:

Be it known that I, SAMUEL J. LARGE, a citizen of the United States, residing at Bristol, Hartford county, Connecticut, have invented a new, original, and ornamental Design for a Handle for a Spoon, Fork, or Similar Article, of which the following is a specification, reference being had to the accompanying drawing, forming part thereof.

In the drawing, the single figure represents a front elevation of a spoon, the handle portion of which embodies my novel design, the outline of a fork being indicated in dotted lines.

I claim:

The ornamental design for a handle for a spoon, fork or similar article as shown.
